AUGUST SUNDH, OF HASTINGS-UPON-HUDSON, NEW YORK, ASSIGNOR TO OTIS
ELEVATOR COMPANY, A CORPORATION OF NEW JERSEY.

ELECTRICAL CONTROL SYSTEM FOR HYDRAULIC TRANSMISSION.

1,288,275.

Specification of Letters Patent. Patented Dec. 17, 1918.

Application filed March 14, 1914. Serial No. 824,780.

To all whom it may concern:

Be it known that I, AUGUST SUNDH, a citizen of the United States, residing at Hastings-upon-Hudson, in the county of Westchester and State of New York, have invented a new and useful Improvement in Electrical Control Systems for Hydraulic Transmission, of which the following is a specification.

My invention relates to an electrical control system, and has for its object the provision of simple and efficient means for controlling a power unit comprising the following elements, a fluid motor, pumping mechanism for supplying fluid under pressure to the fluid motor, and a prime mover such as an electric motor for driving the pumping mechanism.

Other objects of the invention will appear more fully hereinafter, the novel combinations of elements being pointed out in the appended claims.

The accompanying drawing shows electrically operated hydraulic transmission mechanism, and a system of control therefor arranged in accordance with my invention.

The herein following description relating to the hydraulic transmission mechanism, will be brief, since the said mechanism is fully shown and described in detail in my co-pending application, Serial No. 764,994, filed May 2, 1913.

The fluid pressure motor F comprises a plurality of double acting cylinders whose pistons 1 are connected to a common crank pin 2. A driven member 3 comprises a cable sheave 3, which is keyed to the crank shaft and is adapted to receive the hoisting cables of an elevator or other hoist; although if desired the sheave 3 may be replaced by a belt pulley, gear, or other device whereby power may be transmitted from the crank shaft to any desired power consuming device.

The pump P is adapted to deliver fluid under pressure to the fluid motor F. The stroke of the pump plungers 5 is controlled by means of a tilting head 6, carried upon a shaft 7 in anti-friction bearings 8. The right hand end of the tilting head is provided on its inner circumference with a ball race 4, which is secured in place by means of a ring 9 and coating ball race 9', carried by a ring 13, which is concentric with the shaft

7, but is adapted to be shifted in an eccentric position with respect to the shaft 7 by means of a sliding key or wedge 10. The latter is arranged to slide longitudinally in a slot in the shaft by means of a lever 11, which is bifurcated at its lower end and has a pair of oppositely disposed pins which enter a circumferential groove in the part 12, which is integral with the key or wedge 10. By this arrangement the eccentricity of the ring 13 can be varied from zero to maximum in either direction by sliding the wedge lengthwise of the shaft by means of the lever 11. The length of the stroke of the plungers will obviously depend upon the amount of tilt or inclination given to the tilting head by means of the wedge, and since this factor may be varied at will, the output of the pump may be controlled, within predetermined limits, or if desired, the pump may be arranged to reverse the direction of flow of fluid by moving the wedge in a right hand direction past center.

A rotary valve 14 is operated from the pump shaft and is adapted to have a sliding movement thereon. This valve directs the fluid between the pump and fluid motor. Means for imparting a sliding movement of the valve 14 upon the shaft 7, comprises a grooved collar 15, provided on either lateral face with ball thrust bearings which are secured to or carried upon the valve. A pivoted lever 16 has a pin on it which rides in the groove on said collar, the arrangement being such that the valve may be shifted longitudinally of the shaft by means of the lever 16. The latter is provided with a pin 17 at its other end, which pin is adapted to ride in a cam slot 18 formed in the cam 19. The lever 11 by which the wedge 10 is shifted, is also provided with a pin 20, which rides in a cam slot 21 in the cam 22. The cams 19 and 22 are secured to a shaft 23, to which is keyed a worm wheel 24, which is actuated through a worm 25 by means of a pilot motor G. The pilot motor is provided with reversed field windings 26 and 27, by means of which the direction of rotation of the pilot motor and consequently the worm 25 is reversed. Electromagnetic switches 28 and 29 control the circuits of the field windings 26 and 27, respectively. A bar 30 carrying contact strips 31 and 32, is movable

85

90

95

100

105

either to the left or right with the lever 11, said bar being connected to the lever by a link 33. Stationary contacts 34, 34' and 34'' normally engaging the contact strip 31, control a circuit for the winding 28', and stationary contacts 35, 35' and 35'', normally engaging the contact strip 32, control a circuit for the winding 29'. A member 36 is formed integrally with or may be otherwise connected to the bar 30, said member having cam surfaces 37, 37' adapted to actuate a switch 38, and cam surfaces 39, 39' adapted to actuate a switch 40, as hereinafter more fully described.

15 An electric motor M is directly connected to the shaft 7. This motor is of the direct current compound wound type, which is particularly adapted for hoisting purposes, in that it combines the powerful starting torque at low speed of the series wound motor with the substantially constant speed characteristics of the shunt wound motor. The series, shunt and extra field windings are designated A, B and C, respectively.

20 The switch 38 when closed by one or the other of the cams 37 or 37', establishes a short circuit around the series field winding.

25 The switch 40 is normally closed, and when opened by one or the other of the cams 39, 39' opens the circuit of the extra field winding. It is to be noted that the arrangement of the two sets of cams 37, 37' and 39, 39', are such that the switch 40 is opened before the switch 38 is closed thus the extra field

30 winding is cut out before the series field winding is short circuited.

A sectional resistance H in series with the armature of the motor M, is controlled by a plurality of electro-magnetic switches 41, 42, 43 and 44. These switches are provided with windings 41', 42', 43' and 44', whose cores are adjusted in a well known manner to effect the operation of said switches in successive order as above enumerated. The energization of said windings to effect said operation is dependent on the counter-electro-motive force of the rotating armature, since they are connected across or in shunt to the motor armature and a portion of the starting resistance H.

The electric motor M is adapted to drive the shaft 7 in one direction only, and the operation of the driven member 3 in reverse direction is effected by means of the pump, 55 which by moving the wedge 10 in a right or left hand direction past center reverses the direction of flow of fluid.

A winding 45, of the electromagnetic main line switch J is controlled by a switch 60 46, which is controlled by a relay magnet 47. The relay magnet is provided with a dash pot 48, by means of which a time period is obtained when the relay magnet is deenergized, whereby the main line switch 65 will be maintained closed and the motor M

kept running, during the stopping period of the fluid motor F, which time in amount we will say for example, is equal to the average time required in elevator practice to discharge and take on passengers. 70

A manually operable switch D controls the relay magnet 47, and also the pilot motor G. The switch D comprises a pivoted lever 48 carrying contact strips 49 and 50. When the lever is moved to the right the contact 75 49 is adapted to engage contacts 51, 52 and 53, and when moved to the left engages contacts 51', 52' and 53'. A segment 54 supplies current to the contact 50 which spans contact segments 54 and 55 or 54 and 55' 80 when the lever 48 is moved to the right or left, respectively.

The operation is as follows: By moving the contact segments 49 and 50 to the right to engage contacts 51 and 55, respectively, 85 circuits are completed for the windings 47 and 29'. The circuit for the winding 47 is as follows: from the + main to conductor 56 to segment 54 and contact strip 50 to segment 55, conductor 57, winding 47, conductor 58 to - line. The circuit for the winding 29' is as follows: contact 49, contact 51, conductor 59, contact 35 and contact strip 32 to conductor 60, winding 29', to conductors 61 and 62 to - line. The winding 47 90 now being energized will close the switch 46, thereby closing a circuit for the winding 45, the latter thereby closing the main line switch J, which closes a circuit for the motor armature, the series, shunt and extra fields, under which condition the motor will now start running at slow speed, the current taken by the armature being limited by the resistance H. The motor circuit may be traced as follows, from + main through 105 switch J to wire 67, resistance H, wires 68, 69, series field winding to wire 70, through motor armature to wire 71, and thence through switch J to the - line. The winding 29' being energized will close the switch 95 29, thereby closing a circuit for the field winding 27 and armature of the pilot motor G, said circuit being as follows: from + main to conductor 56, junction 56' to conductor 63, through the armature of pilot 110 motor to conductor 64, field winding 27 to conductor 65, through switch 29, and conductor 62 to - line. The pilot motor, through the worm and gear connection will now rotate the cams 19 and 22 a predetermined amount, and in a clockwise direction, we will say for example, looking toward the left on the drawing, thereby moving the valve 14 to the left, and the wedge 10 now being moved to the left off center will tilt 115 the head from a concentric to an eccentric position, whereupon the same will operate and effect the reciprocation of all the pump plungers in their respective cylinders. The pump will now deliver but a small quantity 120

125

130

of fluid to the fluid motor, thereby starting the same at slow speed but with a powerful torque.

It will be noted that the pilot motor will 5 effect a movement of the wedge 10 to change the eccentricity of the head, only a predetermined amount, or in other words, until the lever 11 has moved the strip 32 carried by the bar 30 to the right in this instance, out 10 of engagement with the contact 35, whereupon the circuit for the armature of the pilot motor and field 27 just traced will be opened and the pilot motor will come to rest. Now it will be seen that as the lever 48 is moved 15 farther toward the right so that the contact 49 engages the contacts 52 and 53, respectively, that a predetermined increase in the eccentricity of the head is effected, thereby increasing the output of the pump, and resulting in an increase in the acceleration of 20 the fluid motor to its maximum speed, that is when the contact 49 engages the contact 53. The electric motor will accelerate in proportion to the load thereon, since as the 25 speed of the motor armature increases the windings 41', 42', etc., will be energized, thus effecting the successive operation of the switches 41, 42, etc., in a well known manner, to short circuit the sections of starting 30 resistance H. As the member 36 is moved to the right and at a time when the speed of the fluid motor is almost at its maximum, the cam face 39 on the member 36 actuates the switch 40 thus open circuiting the extra 35 field winding C, and a further movement of said arm effects the closing of the right hand contact of switch 38, thereby short circuiting the series field winding. The motor now accelerates to full speed with all 40 the resistance H, the extra and series field windings cut out, and being excited by the shunt field alone runs at substantially constant speed.

It will be noted that when the bar 30 is in 45 its full right hand position the contact strip 32 is out of engagement with the contact 35'', and the contact strip 31 will be in engagement with a stationary contact 66 and also contacts 35 and 35''. Now as the lever 50 48 is returned to its central position, winding 28' is energized, thus closing a circuit for the field 26 and armature of the pilot motor by means of the switch 28 which will effect the operation of the pilot motor in a 55 reverse direction to that just described, thus effecting the rotation of the cams 19 and 22 to gradually decrease the eccentricity of the head until the same is concentric with the shaft 7, at which time the contact strip 31 60 will have been moved out of engagement with the contacts 35', 35 and 66 and will attain its normal position as shown. The valve 14 is likewise gradually moved to its central or closed position to cut off the fluid 65 supply to the fluid motor, and the fluid is

thus locked in said motor and acts as a brake for the same. The movement of the bar 30 toward its central position reinserts the series and extra fields, thus the motor speed will decrease, and the resistance H 70 will be automatically inserted again, and the motor will run at a slow speed for a period of time determined by the dashpot relay which keeps the main line switch J closed and consequently the motor circuit, 75 for a period of time after the lever 48 is moved to its central position, or in other words after the contact strip 50 disengages the segment 55. Thus it will be seen that electric motor M will not stop each time 80 the fluid motor stops if the time consumed for such stop is not excessive, or more than the average.

By moving the lever 48 toward the left, the fluid motor F is operated in a reverse 85 direction to that herein described. In this operation the field winding 26 is energized by means of the switch 28, thus effecting the operation of said pilot motor to effect the rotation of the cams 19 and 22 in an anti-clockwise direction instead of a clockwise direction as was the case when the lever 48 was moved to the right at starting. This rotation of the cam 22 will move the wedge 10 to the right off center, and thus effect a 90 reverse action of the pump, to that heretofore described, the cam 19 acting the same regardless of its direction of rotation. The mode of operation of the fluid motor and electric motor, will otherwise be the same as 95 heretofore just described and therefore need not be further explained.

It is to be particularly noted that the pilot motor has freedom to rotate the cam 19 in either direction a short distance when 100 the lever 11 is in central position as shown, without the cam slot 21 being effective owing to the straight portion thereof. Such an arrangement is made necessary on account of the difficulty met with by the pilot 105 motor in not stopping directly as it returns the lever 11 to its central position.

Various changes in the details and arrangement of parts might obviously be made by those skilled in the art, without departing from the spirit and scope of the invention. I wish therefore not to be limited to the precise details and arrangement herein shown.

What I claim is:—

1. The combination with a fluid pressure motor, pumping mechanism adapted to supply said motor with fluid under pressure, a non-reversing electric motor for driving the pumping mechanism, a pilot motor, means 115 actuated thereby for varying the output of the pump, means for controlling the pilot motor to effect the starting, stopping and variation in the speed of the fluid motor in either direction independently of the elec- 120 125 130

tric motor, a manually controlled electro-magnetic switch for controlling the starting and stopping of the electric motor, and means for automatically regulating the acceleration of the electric motor in proportion to the load thereon.

2. The combination with a fluid pressure motor, pumping mechanism for supplying fluid under pressure to said motor, a non-reversing electric motor for driving the pumping mechanism, a pilot motor, means actuated thereby for directing fluid from the pump to the fluid motor and for simultaneously varying the output of the pump independently of the electric motor, a manually operable switch, means controlled thereby for controlling the pilot motor to effect the starting, stopping and variation in speed of the fluid motor in either direction, an electromagnetic switch controlled by said switch for connecting and disconnecting the electric motor with a source of current supply, and means for automatically accelerating the electric motor in proportion to the load thereon.

3. The combination with a fluid pressure motor, pumping mechanism adapted to supply said motor with fluid under pressure, an electric motor for driving the pumping mechanism, said motor having a series, shunt, and extra field windings, a manually operable switch, an electromagnetic switch controlled thereby for connecting and disconnecting the electric motor with a source of current supply, means controlled by said switch for controlling the starting, stopping and speed of the fluid motor, a starting resistance in series with the armature of said electric motor, electro-responsive mechanism for automatically cutting out said resistance as the speed of the motor increases, and means operable when the fluid motor reaches a predetermined speed, to automatically short circuit the extra and series field windings substantially as described.

4. A driving and driven member, power transmission mechanism interposed between said members, means for controlling the starting, stopping and the acceleration of the power transmission mechanism at will, and means for controlling the starting and stopping of the driving member, said means being arranged automatically to maintain the operation of the driving member for a predetermined period of time, relative to the stopping period of the power transmission mechanism.

5. The combination with fluid power transmission mechanism, an electric motor for driving the same, a manually operable switch, means controlled thereby for starting and stopping the power transmission mechanism, and means controlled by said switch for connecting and disconnecting the motor with a source of current supply, said means

being arranged automatically to maintain a supply of current to said motor for a predetermined period of time after the stopping of the power transmission mechanism.

6. The combination with fluid power transmission mechanism, a manually operable switch, means controlled thereby for starting and stopping the fluid power transmission mechanism, an electro-magnetic switch for connecting and disconnecting the motor with a source of current supply, and means for controlling the operation of said switch to maintain a supply of current to the motor armature for a predetermined period of time when the power transmission mechanism is stopped by moving the manually operable switch to its normal or central position.

7. The combination with a driving and driven member, power transmission mechanism interposed between said members, means to start the driving member and transmitting mechanism simultaneously, and means to stop the transmitting mechanism and to effect the stopping of the driving member in a predetermined period of time after the stopping of the transmitting mechanism.

8. The combination with a driving member and driven member, variable speed power transmission mechanism interposed between said members, means for starting and stopping the driving member and power transmission mechanism, and a timing device to automatically effect the stopping of the driving member in a predetermined period of time after the stopping of the transmission mechanism.

9. The combination with variable speed power transmission mechanism, manually operative means for controlling the starting, stopping and acceleration of said mechanism, a driving member for the power transmission mechanism, manually operative means for starting said member, said manually operative means for both the power transmission mechanism and the driving member being adapted to effect the stopping of the transmission mechanism and the driving member, and a timing device for automatically maintaining the driving member in operation for a predetermined period of time after the stopping of the transmission mechanism.

10. The combination with a fluid pressure motor, pumping mechanism adapted to supply said motor with fluid under pressure, an electric motor for driving the same, a pilot motor, and means actuated thereby for varying the output of the pump, said means being arranged so that the pilot motor may have a certain amount of play at starting.

11. The combination with a fluid pressure motor, pumping mechanism adapted to supply said motor with fluid under pressure, a

non-reversing electric motor for driving the same, a reversible pilot motor, means actuated thereby for varying the output of the pump, said means being arranged so that 5 the pilot motor may have a certain amount of play in either direction at starting.

12. The combination with a fluid pressure motor, pumping mechanism adapted to supply said motor with fluid under pressure, an 10 electric motor for driving the pumping mechanism, a pilot motor, means actuated thereby for directing fluid from the pump to the fluid motor and for simultaneously varying the output of the pump independently 15 of the electric motor, a switch controlled by said means for automatically controlling the pilot motor to effect a step by step variation in the output of the pump, and a manually operative switch for controlling supply circuits to the first named 20 switch.

13. The combination with a fluid pressure motor, pumping mechanism adapted to supply said motor with fluid under pressure, an 25 electric motor for driving the pumping mechanism, said motor having a series, shunt and extra field windings, a center shifting device associated with the pump, a pilot motor for actuating the same, a 30 manually operable switch, an electro-magnetic switch controlled thereby for connecting and disconnecting the electric motor with a source of current supply, means controlled by said switch for controlling the 35 pilot motor to effect the starting, stopping and variation in speed of the fluid motor, a starting resistance in series with the armature of said electric motor, electro-responsive mechanism for automatically cutting out 40 said resistance as the motor speed increases, and means dependent on the movement of the center shifting device for automatically cutting out the extra and series field windings when the pump stroke is almost at its 45 maximum.

14. A driving and driven member, power transmission mechanism interposed between

said members, means for controlling the operation of the power transmission mechanism at will in either direction and the driving member in one direction, an electric motor, and means dependent upon the counter-electro-motive force of the motor for automatically regulating the speed of the driving member in proportion to the speed of the 50 driven member.

15. The combination with a fluid pressure motor, a pumping mechanism adapted to supply said motor with fluid under pressure, a non-reversing electric motor for driving 55 the pumping mechanism, manually controlled electro-responsive means for starting, stopping and accelerating the fluid motor in either direction mechanically, independently of the electric motor, manually controlled 60 means for controlling the starting and stopping of the electric motor, and means for automatically regulating the speed of the electric motor in proportion to the load and 65 speed of the fluid motor.

16. The combination with a fluid pressure motor, pumping mechanism adapted to supply said motor with fluid under pressure, a non-reversing electric motor for driving 70 the pumping mechanism, electro-responsive 75 means for starting, stopping and accelerating the fluid motor in either direction mechanically, independently of the electric motor, an electro-magnetic switch for connecting and disconnecting the electric motor 80 with a source of current supply, a manually operable switch for controlling the said electro-responsive means and said electro-magnetic switch, and means for automatically accelerating the electric motor in proportion 85 to the load on the motor.

In testimony whereof, I have signed my name to this specification in the presence of two subscribing witnesses.

AUGUST SUNDH.
